UNITED STATES PATENT OFFICE.

WILLIAM G. KENDALL, OF NEWARK, NEW JERSEY.

PARTITION FOR VANITY CASES.

Application filed October 14, 1920. Serial No. 416,847.

To all whom it may concern:

Be it known that I, WILLIAM G. KENDALL, a citizen of the United States, residing at Newark, in the county of Essex and State 5 of New Jersey, have invented certain new and useful Improvements in Partitions for Vanity Cases, of which the following is a specification.

This invention relates to improvements in vanity cases of that type designed to contain compressed powder pads and more particularly to an improved partition member for dividing the interior of the case into two compartments, each receiving an individual one of the pads.

One of the objects of the invention is to provide a partition member of such construction that it may be readily stamped or otherwise formed from a single integral rectangular sheet metal blank and will therefore be inexpensive to manufacture.

Another object of the invention is to so construct the partition member that it will be firmly supported and retained in place 25 within the vanity case when positioned therein.

Another object of the invention is to provide a partition member for use in the connection stated which member will add to 30 the artistic appearance of the case rather than detract from such appearance.

In the accompanying drawing:

Figure 1 is a plan view of a vanity case equipped with the partition member embodying the invention, the lid of the case being shown swung to open position to better disclose the partition member;

Figure 2 is a vertical longitudinal sectional view through the case;

Figure 3 is a perspective view of the partition member removed from the case;

Figure 4 is a perspective view of the sheet metal blank from which the partition member is to be stamped or otherwise formed.

In the drawings the body of the vanity case is indicated in general by the numeral 1 and the usual hinged lid by the numeral 2. The said body 1 comprises a rear wall 3, a front wall 4, end walls 5, and a bottom 6.

The compressed powder pads which are to be retained within the body of the vanity case are indicated by the numeral 7 and in the present instance there are two such pads and they are to be individually housed within

compartments formed by dividing the interior of the body of the case by disposing

within the body the partition embodying the invention.

The partition embodying the invention is indicated in general by the numeral 8 and 60 the same comprises two side members each having an intermediate portion 9, portions 10 which extend at obtuse angles in opposite directions from the portion 9, and terminal portions 11 which extend at obtuse 65 angles from the ends of the respective portions 10 and which occupy planes at right angles to the plane of the respective intermediate portion 9. At this point it may be stated that the portions 10 and 11 might be 70 merged along curved lines if found desirable although there is an advantage for forming these portions in such manner that they will be relatively angularly disposed, as will be presently pointed out. The side members 75 comprising the partition are integrally united along one margin of their intermediate portions 9 by an integral connecting portion or bend 12, the said portions 9 lying side by side and preferably in contact. In 80 assembling the partition member with the vanity case, the said member is disposed within the mid portion of the body of the case in the position clearly shown in Figures 1 and 2 of the drawing and with the end portions 11 of the side members of the partition resting flat against the inner faces of the rear and front walls of the said body of the case, the lower edges of the side members of the partition resting in contact with 85 the upper surface of the bottom 6 of the said case. The end walls 5 of the body of the vanity case are of arcuate form and by reference to Figure 1 it will be observed that the extremities of the terminal portions 11 90 of the side members of the partition are located substantially at the point where the end walls 5 merge with the rear and front walls of the body of the case. Consequently 95 when the partition is fitted into the body of the case it will be retained in a position midway between the ends of the said body for the reason that any endwise displacement of the partition would result in the central portions of the side members riding 100 against the curved end walls 5 which would tend to force the terminal portions toward each other, but this is resisted due to the inherent resiliency of the metal from which the partition is formed. Also if the terminal portions 11 are formed flat as illustrated 105 in the drawings, they will have maximum 110

area bearing frictionally against the faces of the rear and front walls of the case body so as to further resist any endwise displacement of the partition within the body. The 5 partition when disposed within the body divides the body into two compartments, and into these compartments may be readily fitted the compressed powder pads 7 which pads will then be separated so that dust from 10 one cannot commingle with the other. Also the case is designed to contain powder puffs which are indicated by the numeral 13 and which will be maintained separated by the said partition.

15 The partition embodying the invention is, as previously stated, formed from a single integral metal blank which is illustrated in Figure 4 of the drawings and is indicated by the reference letter A. This blank is of 20 rectangular form and preparatory to stamping up of the blank it is formed with longitudinally extending incisions B along its medial line which incisions terminate at their inner ends in spaced relation so that 25 when the blank is folded up the intervening portion will provide the connecting bend 12.

Having thus described the invention, what is claimed as new is:

1. A partition for vanity cases and the like 30 comprising side members having intermediate portions lying side by side, and end

portions extended to embrace an article to be retained within the case, the said intermediate portions being marginally united.

2. A partition for vanity cases and the like 35 comprising side members having intermediate portions marginally united, and upright embracing portions extending laterally in opposite directions from the intermediate portion.

3. A partition for vanity cases and the like 40 comprising side members having intermediate portions lying side by side and marginally connected, portions extending obliquely from the ends of the intermediate 45 portions, and terminal portions extending at an angle from the oblique portions.

4. The combination with a vanity case 50 having front and rear walls and connecting end walls, and a partition disposed within the case and comprising side members having intermediate portions marginally connected and having terminal portions bearing frictionally against the inner faces of the front and back walls of the case and 55 having their extremities located substantially at the point of juncture of the end walls of the case with the said front and back walls.

In testimony whereof I affix my signature. 60

WILLIAM G. KENDALL. [L. s.]
